(57) **CLAIM**

The ornamental design for a bolus button, as shown and described.

DESCRIPTION

FIG. 1 is a perspective view showing the front, right side, and bottom of a bolus button in accordance with our new design;

FIG. 2 is a right side elevation view of the bolus button of FIG. 1;

FIG. 3 is a left side elevation view of the bolus button of FIG. 1;

FIG. 4 is a front plan view of the bolus button of FIG. 1;

FIG. 5 is a back plan view of the bolus button of FIG. 1;

FIG. 6 is a top elevation view of the bolus button of FIG. 1; and,

FIG. 7 is a bottom elevation view of the bolus button of FIG. 1.

The broken lines show portions of the bolus button that form no part of the claimed design.
